(57) **CLAIM**

The ornamental design for an esophagus sizing instrument, as shown and described.

DESCRIPTION

FIG. 1 is a top perspective view of an esophagus sizing instrument, showing our new design;

FIG. 2 is a top plan view thereof;

FIG. 3 is a left side elevational view thereof (the right side elevational view being a mirror image of the left side elevational view shown in FIG. 3);

FIG. 4 is a bottom plan view thereof;

FIG. 5 is a front elevational view thereof; and,

FIG. 6 is a back elevational view thereof.

The shaft shown in broken lines is unclaimed environment and forms no part of the claimed design.
